DESIGN FOR A BEACH BAG

Florence N. Lewis, New York, N. Y.

Application July 1, 1938, Serial No. 78,207

Term of patent 3½ years

To all whom it may concern:

Be it known that I, Florence N. Lewis, a citizen of the United States, residing at New York, in the county of New York and State of New York, have invented a new, original, and ornamental design for a Beach Bag, of which the following is a specification, reference being had to the accompanying drawing, forming part thereof.

In the drawing

Fig. 1 is a perspective view of a beach bag showing my new design in closed position;

Fig. 2 is a perspective view showing the front pocket of the bag in opened position.

Fig. 3 is a perspective view showing the rear pocket of the bag in opened position.

I claim:

The ornamental design for a beach bag, as shown and described.

FLORENCE N. LEWIS.
